UNITED STATES PATENT OFFICE

TROY R. LIVINGSTON, OF MUNCIE, INDIANA, ASSIGNEE, BY MESNE ASSIGNMENTS,
TO THE DELPHOS BENDING COMPANY, OF DELPHOS, OHIO, A CORPORATION OF
OHIO

ROLL STRUCTURE FOR DRY-WOOD-BENDING MACHINES

Application filed September 8, 1928. Serial No. 304,669.

My invention relates to a roll structure, especially adapted for use in the heated rolls of dry-wood bending machines of the character shown in Patents Nos. 960,525 and 1,507,368, granted to Charles W. Elliott on June 7, 1910, and September 2, 1924, respectively.

In such dry wood bending machines, there is a heated roll which is heated internally, usually by gas flames, and which is mounted for rotation to co-operate with other rolls to produce the permanent bending of dry strips of wood. The heated rolls of these machines are subjected to tremendous stresses, not only from the mechanical action and re-action against the wood being bent, but even more markedly as the result of stresses within the roll itself. As the heated roll is a composite structure, with a cylindrical peripheral member and separate supporting end members, the stresses which are produced make ordinary fastening devices, such as screws, practically impossible as permanent attaching members; because such screws work loose in a relatively short space of time.

It is the object of my present invention to provide a roll structure in which the attaching means between the parts of the roll will not become loose in operation, and in which the changes in size and shape due to changing temperatures are not opposed by the attaching means but are permitted to work themselves out harmlessly.

The accompanying drawing illustrates my invention: Fig. 1 is a transverse vertical section, substantially on the line 1—1 of Fig. 2, of a fragment of a dry-wood bending machine, having a heated-roll structure embodying my invention; and Fig. 2 is a longitudinal section through the heated roll, taken substantially on the line 2—2 of Fig. 1.

The dry-wood bending machine has a heated roll 11 which co-operates with two supplemental rolls 12 and 13 to produce bending of strips of wood 14 as they are fed through the machine. The heated roll 11 acts on the side of the wood which is to be concave, and the other two rolls act on the other side of the wood. One of the rolls, desirably the heated roll, is suitably power-

driven, for which purpose it has a driving gear 15. The action of the rolls may be supplemented by a flexible sheet of metal 16 which extends between the rollers 12 and 13 and the wood strips 14; and by pressure rollers 17 which act against the outer face of the metal sheet 16 at about the place where the bending of the wood starts, which is between the two rollers 12 and 13.

The rollers 11, 12, and 13 are all carried by a supporting frame 18, so that they may rotate to feed the wood 14 through from left to right (Fig. 1).

The heated roll 11 is heated by the flames from a gas burner 21, which is conveniently a gas pipe with suitable holes through it for the flames. This gas pipe is supported by a stationary rod or pipe 22 located on the axis of the roll 11 and supplying the gas to the burner 21. The rod or pipe 22 is stationarily supported from the frame 18, and furnishes the bearing support for the heated roll 11.

As thus far generally described, the structure is known. My invention relates to the structure of the roll itself.

The heated roll 11 comprises a cylinder 25, which bears against the surface of the wood strip 14. This cylinder 25 is of suitable metal, sufficiently heavy to exert the necessary pressure; and may be made as a casting or forging or as a length of standard heavy tubing. The cylinder 25 is carried by two end members 26 and 27, which have bearing support on the rod or pipe 22 with interposed bushings 28 if desired. The end member 27 is desirably of one piece with the gear 15. The end members 26 and 27 have outwardly projecting radial spokes 30 and 31, which fit within the ends of the cylinder 25 and abut against the inner surface thereof. The spaces between the spokes, at least those of the end member 26 which does not carry the gear though if desired also between those of the end member 27, are open spaces, to provide outlet passages from the roll for the products of combustion from the gas flames.

The spokes 30 and 31 support the cylinder at points sufficiently angularly close to prevent any marked distortion of such cylinder; such as might occur by the collapsing of the

cylinder between spokes if the spokes were too far apart.

Registering radial holes are drilled in the cylinder 25 and in the ends of some of the spokes 30 and 31. Conveniently such holes are provided in alternate spokes, as is clear from Fig. 1; and those spokes are in consequence conveniently made thicker than the other set of alternate spokes. In these radial holes are set plugs 35, which extend in radially and do not interfere with any relative radial movement between the spoke 30 or 31 and the superposed portion of the cylinder 25, such as may occur upon differential heating of the cylinder and end members. That is, the plugs 35 have in the holes which receive them, or at least in the holes in the cylinder 25, a fit which is sufficiently loose to permit sliding; although that does not need to be very loose, on account of the tremendous stresses which are involved in heating and cooling. Near their inner ends, each plug 35 is provided with a circumferential groove 36; which receives the inner end of a screw plug 37 which is screw-mounted in the spoke 30 or 31 that carries the associated pin 35 and projects parallel to the axis of the roller or perpendicular to the pin 35.

It is found that this construction makes a permanent attachment between the end members 26 and 27 and the cylinder 25, which does not become loose in use. That is, the pins 35 are not subjected to stresses, as screws would be, from differential expansion and contraction of the cylinder 25 and of such end members but permit free radial movement between such end members and the cylinder 25, while providing between them an attachment entirely sufficient to transmit any torques encountered in practice.

If it is desired to take the roll apart, as for inspection or repair, this can readily be done by first removing the screw plugs 37 and then lifting out the pins 35.

45 I claim as my invention:

1. A roll structure, comprising a cylinder, end members fitting within the ends of the cylinder, said end members and the overlying parts of the cylinder having registering holes, pins set in said holes to hold the cylinder and end members together while permitting radial movement between them, said pins being provided with circumferential grooves, and means mounted in the end members and projecting into said circumferential groove to hold the pins in place.

2. A roll structure, comprising a cylinder, end members fitting within the ends of the cylinder, said end members and the overlying parts of the cylinder having registering holes, pins set in said holes to hold the cylinder and end members together while permitting radial movement between them, said pins being provided with circumferential grooves, and screw plugs mounted in the end members and

projecting into said circumferential groove to hold the pins in place.

3. A heated-roll structure for dry-wood bending machines, comprising two end members for rotatably mounting on a supporting rod, a driving gear integral with one of said end members, said end members being provided with radially projecting spokes, a cylinder within the ends of which said spokes lie so that said spokes abut against the inner surface of the cylinder, the ends of one or more of the spokes and the cylinder being provided with registering holes, pins set in said holes and permitting free relative radial movement of the cylinder and spokes upon differential expansion and contraction due to heating and cooling, said pins being provided with circumferential grooves, and means mounted in the spokes for engaging said grooves to hold the pins radially in place in the spokes.

4. A heated-roll structure for dry-wood bending machines, comprising two end members for rotatably mounting on a supporting rod, a driving gear integral with one of said end members, said end members being provided with radially projecting spokes, a cylinder within the ends of which said spokes lie so that said spokes abut against the inner surface of the cylinder, the ends of one or more of the spokes and the cylinder being provided with registering holes, pins set in said holes and permitting free relative radial movement of the cylinder and spokes upon differential expansion and contraction due to heating and cooling, said pins being provided with circumferential grooves, and means mounted in the spokes for engaging said grooves to hold the pins radially in place in the spokes.

5. In a roll structure, a hollow cylinder and end members fitting within the ends of the cylinder, said end members and the overlying parts of the cylinder having registering holes extending radially of said cylinder, said holes being of uniform cross-section, and pins located in said registering holes in the end members and cylinder, each of the pins being secured to one of said parts and being of uniform cross-section where it is received in the other part in order to permit relative radial movement of the cylinder and end members while holding them in definite angular relation.

6. In a heated-roll structure, a hollow cylinder, an end member in one end of said cylinder having a driving gear integral with itself, an end member in the other end of said cylinder, radially projecting spokes on said end-members abutting the inner surface of said cylinder, one or more of the spokes and the over-lying parts of the cylinder being provided with registering holes of uniform cross-section, and pins fitted in said holes, each of said pins being fastened in one of

said parts and being of uniform cross-section where it is received by the other part in order to permit relative radial movement of the cylinder and the end members while holding them in definite angular position.

5 7. A roll structure, comprising a hollow cylinder, a driving end member for said cylinder adapted to be rotatably mounted, another end member for said cylinder, means operatively connecting said driving end member and said cylinder, said connecting means including a radially extending pin carried by one of said inter-connected parts and fitted in a hole of uniform cross-section in the other 10 of said interconnected parts in order to permit relative radial movement of said interconnected parts while holding them in definite angular adjustment.

15 In witness whereof, I, T. R. LIVINGSTON, have hereunto set my hand at Muncie, Indiana, this 5th day of September, A. D. one thousand nine hundred and twenty-eight.
